UNITED STATES PATENT OFFICE.

KARL ARNSTEIN, OF FRIEDRICHSHAFEN, GERMANY, ASSIGNOR TO THE FIRM LUFT-SCHIFFBAU ZEPPELIN GESELLSCHAFT MIT BESCHRANKTER HAFTUNG, OF FRIEDRICHSHAFEN, GERMANY.

LIGHT-WEIGHT GIRDER.

Application filed June 28, 1920. Serial No. 392,486.

(GRANTED UNDER THE PROVISIONS OF THE ACT OF MARCH 3, 1921, 41 STAT. L., 1313.)

To all whom it may concern:

Be it known that I, KARL ARNSTEIN, a citizen of the Czechoslovakia Republic, residing at Friedrichshafen, Germany, have invented 5 certain new and useful Improvements in Light-Weight Girders (for which I have filed application in Germany, March 1, 1918), of which the following is a specification.

10 My present invention relates to articulated light weight girders such as are, for example, employed as longitudinal girders for the supporting planes of flying machines. Now 15 constructional elements of this kind are expected, while having a great length and comparatively low height, to produce a very slight bend, the smallest possible weight, and to be to a considerable extent proof against axial compression.

20 In the case of the hitherto known forms of articulated girders, the panel work is generally composed of a continuous tubular or else solid bar, which has to be bent or flattened at the joints. Sometimes, too, strip-shaped stays or trusses are also employed 25 for this purpose, produced by rolling or drawing, which are throughout of equal width. In the first case, the stays will turn out to be heavy, and will have their strength 30 impaired by subsequent deformation. In the second case, the attachment will prove particularly difficult.

35 My present invention is intended to obviate these drawbacks by a special shaping given to said stays or trusses, as also by the peculiar method devised for their interconnection. The improved articulated light-weight girder therefore comprises either 40 channel-shaped or V-shaped girder cross sections filled in with stays or trusses arranged crosswise. In accordance with this invention, these single trusses are stamped of sheet metal and are suitably riveted at the joints. With the view to increasing the 45 strength of the structure, the cross section of these stays embodies a flanged longitudinal groove. Besides this, they are correspondingly enlarged at the joints, so that rivet 50 connections may be readily produced. As the stays are formed by a stamping process, they may be provided by a single working operation with any peculiar shape that may

be desired for each particular case. Moreover, the single pairs of stays may be combined to form cross-shaped structures, and this in the most convenient manner imaginable even before they are riveted to the tie sections, so that the construction of the complete girder will be very much simplified. 60

This improved structure embodies a substantial advance over and above girders having sheet metal panel work structures, inasmuch as the radius of gyration is increased, and also because, owing to the interconnection of the drawn and the stamped stays or trusses, the extent of the bending stress is halved. 65

If now the intercrossed stays be alternately connected within and without to the flanged portions of the ties, then the trusses may be riveted to one another at the points of intersection by mutually bridging the flattened sections thereof, facing each other and symmetrically disposed toward one another, without requiring the one stay to be bent off to a greater extent relatively to the other. 70

75 It will, however, at times appear of advantage to cause the stays to repeatedly intersect or cross each other, in consequence of which the separate lengths subject to bending stress will be still more reduced, since the stays which in accordance with the invention may be riveted to each other at the point of connection will be further shortened. According to the nature of the stress arising, this method of arrangement for the stays may, say, for example, in the case of box-section girders, be restricted to the lateral 80 portions thereof, or else all the walls may be composed of stays, repeatedly intercrossing each other, stamped out of sheet metal, having a cross section embodying a flanged longitudinal groove, and suitably enlarged 85 at the points of connection. 90

95 Several forms of execution of the subject matter of this invention are disclosed by way of example in the accompanying drawings, in which:

100 Fig. 1 is a side view of a girder,

Fig. 2 a cross section, on an enlarged scale, through a pair of intercrossed stays along line 2-2 in Fig. 1,

Fig. 3 a side view of the lower portion of an intercrossed stay structure,

Fig. 4 a cross section along line 4—4 in Fig. 3,

5 Fig. 5 a longitudinal section along line 5—5 in Fig. 3,

Fig. 6 a cross sectional view of the angular profile formation of a box-section girder,

10 Fig. 7 a side view of the same,

Fig. 8 a sectional view along line 3—3 in Fig. 7, as viewed from below,

15 Fig. 9 a sectional plan view of the lower tie section along line 4—4 in Fig. 7, as viewed from above, and

Fig. 10 a side view of a modified form of girder construction.

In the form of construction shown in Figs. 1 to 5, the girder is composed of two thin 20 chord bars *a* and *b* of angle-shaped section, on the flanges of which there are riveted stays *c* arranged crosswise. Each of these intercrossings comprises two completely 25 identical stays, of which always the one is riveted to the inside faces, and the other to the outside faces of the chord flanges.

Each stay *c* is provided with a through-going longitudinal groove. In addition, each stay is enlarged at the centre, as also 30 at the ends in the manner of a shackle, or the like. Besides, the said stays are provided with a flange or beading extending across their two longitudinal edges, while the two cross edges running parallel to the 35 edges of the chords are not flanged. Owing to the provision of the longitudinal groove, the central enlargement, and the edge flanging, each single stay is in any case already to a high degree secured against bending 40 stresses. The strength of the structure is, however, still more and substantially enhanced by the fact of the groove and the edge flanging being turned away from the plane of symmetry in the case of each intercrossed structure, and that owing to the 45 fact of the tie flanges being but rather thin, the flat, central stay sections may be riveted together without requiring the one or the other stay to be turned or bent down.

50 Figs. 6—10 disclose a box-girder, the chord members of which have an angular profile formation. These latter are mutually connected by means of stays or intercrossed stay structures. In Fig. 6, *a* denotes the angular profile formation of the upper, and *b* that of the lower tie member. In Fig. 7, the intercrossed stay structures *c* are riveted to the chord members *a* and *b*, respectively. In the arrangement according 55 to Fig. 8 the angular members *a* are interconnected by plain stays *d*. Subject to Fig. 9, the angular chord members *b* are interconnected in a manner similar to that of the lateral walls of the girder, by means 60 of intercrossed stay structures *d'*.

For mere convenience, the stays belonging to the lateral walls of the girder, which would otherwise be seen in section, are not shown in Figs. 8 and 9.

In these last-mentioned two forms of construction the intercrossed stay structures, respectively, the single stays, always comprise stays of like shape and character having a continuous longitudinal groove and a flanging at their longitudinal sides. At 70 their extremities (in the case of the intercrossed structures also at the centre) the said stays are suitably enlarged to the form of a shackle, to render a rivet connection possible.

The form of construction shown in Fig. 80 10 relates to a comparatively high form of light girder, the stays of which are arranged so as to repeatedly intercross. In this arrangement, the stays *d* are riveted to the chords *e*; said stays being likewise provided with the through-going central groove, lateral flanges and shackle-like enlargements both at the extremities as also at all the 85 points of intersection, for the purpose of rendering a rivet connection possible. 90

I claim:—

1. A girder comprising two longitudinal elements or chords and two rows of panel rods, the ends of the rods of one row being fixed to one side of said chords, the ends of 95 the rods of the other row to the other side, each rod of one row crossing a rod of the other row and being fixed thereto at the crossing point.

2. A girder comprising two longitudinal 100 elements or chords and two rows of sheet metal panel rods, the ends of the rods of one row being fixed to one side of said chords, the ends of the rods of the other row to the other side, each rod of one row crossing a rod of the other row and being fixed thereto at the crossing point. 105

3. A girder comprising two longitudinal elements or chords and two rows of longitudinally grooved sheet metal panel rods, 110 the ends of the rods of one row being fixed to one side of said chords, the ends of the rods of the other row to the other side, each rod of one row crossing a rod of the other row and being fixed thereto at the crossing point. 115

4. A girder comprising two longitudinal elements or chords and two rows of panel rods, the broadened ends of the rods of one row being fixed to one side of said chords, the broadened ends of the rods of the other row to the other side, each rod of one row crossing a rod of the other row and being fixed thereto at the crossing point. 120

5. A girder comprising two longitudinal elements or chords and two rows of panel rods, the broadened ends of the rods of one row being fixed to one side of said chords, the broadened ends of the rods of the other row to the other side in two places, each rod 125 130

of one row crossing a rod of the other row and being fixed thereto at the crossing point.

6. A girder comprising two longitudinal elements or chords and two rows of panel rods, the broadened ends of the rods of one row being fixed to one side of said chords, the broadened ends of the rods of the other row to the other side in two places, each rod of one row crossing a rod of the other row 10 and being fixed thereto at the crossing point in two places.

7. A girder comprising two longitudinal elements or chords and two rows of panel rods, the ends of the rods of one row being 15 fixed to one side of said chords, the ends of the rods of the other row to the other side, each rod of one row crossing several rods of the other row and being fixed thereto at the crossing points.

8. A girder comprising two longitudinal elements or chords and two rows of sheet metal panel rods with partly beaded lateral edges, the ends of the rods of one row being fixed to one side of said chords, the ends of 25 the rods of the other row to the other side, each rod of one row crossing a rod of the other row and being fixed thereto at the crossing point.

9. A girder comprising two longitudinal elements or chords and two rows of panel rods, the broadened ends of the rods of one 30 row being fixed to one side of said chords,

the broadened ends of the rods of the other row to the other side, each rod having a broadened portion intermediate its ends and 35 crossing a rod of the other row with the broadened portions coinciding and being fixed to one another in two places.

10. A girder comprising two longitudinal elements or chords and two rows of sheet metal panel rods with partly beaded lateral edges, the ends of the rods of one row being fixed to one side of said chords, the ends of 40 the rods of the other row to the other side, each rod having a broadened portion intermediate its ends and crossing a rod of the other row with the broadened portions coinciding and being fixed to one another in 45 two places.

11. A girder comprising two longitudinal elements or chords and two rows of panel rods, the broadened ends of the rods of one row being fixed to one side of said chords, the broadened ends of the rods of the other row to the other side, each row having several 50 broadened portions intermediate its ends and crossing several rods of the other row with the broadened portions of the inter-crossed rods coinciding and being fixed to 55 one another in two places.

In testimony whereof I affix my signature.

KARL ARNSTEIN.
